UNITED STATES PATENT OFFICE.

MEIER GEORGE HILPERT, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

TURNTABLE.

Application filed October 26, 1921. Serial No. 510,428.

To all whom it may concern:

Be it known that I, MEIER GEORGE HILPERT, a citizen of the United States, and resident of Bethlehem, county of Northampton, 5 State of Pennsylvania, have invented certain new and useful Improvements in Turntables, of which the following is a specification.

My invention relates to turntables for reversing locomotives and other rolling stock, 10 or transferring them to a different track alignment. More particularly, the invention comprises improvements in the construction of turntables of the multiple-span type, such as shown in my Patent No. 1,324,820 patented Aug. 3, 1920. Turntables of this type include, in general, a pair of spans, supported at their inner ends on a vertical pivot and having trucks at their 15 outer ends running on a circular track whose center is the pivot point. For the purpose of centralizing on the pivotal support the stresses produced by the rolling stock, the girders constituting the spans are connected 20 at their inner ends to a central cross girder by a hinge or flexible connection permitting a slight flexing of the spans about a transverse horizontal axis lying in or adjacent the vertical plane passing through the pivot 25 point; the axis of flexure, or in other words, the line of no flexure, being located well above the lower flanges of the girder. In order to make the table a rigid structure with reference to lateral and longitudinal 30 stresses, there is provided for each span a lateral bracing system disposed between the two girders of each span and which is rigidly connected to said central girder in a line coincident with the line of no flexure, 35 the said lateral system being carried around the meeting ends of the spans in a plane including the line of no flexure, thus permitting a slight bending of the table about the line of no flexure, but rigidly sustaining and 40 transmitting all lateral stresses.

In the operation of the table, lateral 45 stresses of considerable magnitude are sometimes produced as when the motors driving the two ends of the table are unequally braked or when only one motor is being driven or 50 when the table is provided with a motor only at one end, and since these stresses are a maximum in the center panels of the ta-

ble where the spans are discontinuous, it has been found desirable to take care of 55 these stresses by a special reinforcement. One of the features of my invention resides in an improved lateral bracing system around the flexible connection which provides a deep outside truss for the two central panels on both sides of the table and 60 extending longitudinally on both sides of the flexible connections. Another feature of my invention comprises, in connection with said lateral bracing system, a centrally disposed tower, or arch, passing over the table and providing support for the collector rings and conductors which convey power 65 to the motors. This latter feature of my invention provides for an aerial, or overhead, system of current supply which, for 70 obvious reasons of safety and convenience, is very desirable; and which furthermore, by eliminating the necessity of leading the power conductors up through the pivotal axis of the table, makes it possible to employ a central cross girder of very simple and 75 strong construction. The power-intake tower or arch is preferably supported directly on the outside lateral system and is 80 braced transversely and longitudinally with respect to the table by a novel system which permits the slight flexing of the table referred to above.

In the accompanying drawings:

Figure 1 is a plan view of a turntable embodying my improvements, showing the power intake arch in section;

Figure 2 is a side elevation of the table with parts broken away;

Figure 3 is a diagrammatic view, illustrating the connections between the central girder, the lateral system and the power-intake arch, and indicating the method of bracing the latter to the span girders;

Figure 4 is a transverse vertical section of the complete table, showing the power-intake arch in elevation;

Figure 5 is a transverse vertical section on a larger scale, showing the central cross 100 girder in elevation and, also gussets of main lateral bracing system and details of supports for lateral system and arch;

Figure 6 is a horizontal section on line 6-6 of Figure 5; and

Figures 7 and 8 are detail views illustrat-

ing connections for supporting and bracing the power-intake arch.

Referring particularly to Figures 1 and 2, the turntable comprises a pair of spans, designated generally by the reference letters A and B. Each span consists of a pair of parallel girders each comprising a pair of girder elements 1 built up structurally in the form of an I beam, and connected by a transverse bracing system, 2, adapted to sustain and transmit lateral stresses, the webs of the girder elements being stiffened by inner and outer vertical angle pieces 3, riveted thereto at suitable intervals. The inner ends of the girders, or spans, are connected to a cross girder 4, which is pivoted on a support 5 for rotation in a horizontal plane. Attached to the outer ends of the girders are platforms 6, on which are mounted electric motors 7 operating the driving wheels 8 through suitable gear and braking connections. The outer ends of the girders are additionally supported on the circular track by a number of wheels arranged in tandem, all of the wheels being of course journaled on axes which converge in the central pivot axis of the table.

The central girder 4 consists of a single reinforced plate disposed between the ends of the spans and in the embodiment illustrated projecting a substantial distance beyond the sides of said spans. (See Figure 6.) This girder plate, as shown in Figure 5, has its lower central portion cut away to a line which, as will be pointed out presently, is approximately coincident with the axis of flexure of the table. Riveted on each side of plate 4 are upper and lower horizontal angle pieces 9 and 10 and vertical angle pieces 11, the riveting surfaces of the latter being provided by the stiffening plates 12. This construction provides a light but very strong girder and is a decided improvement over the construction shown in my patent, above referred to, which construction was of necessity built up to provide a central conduit for the power conductors. By providing an aerial system of current supply, I am enabled to form the cross girder of a single continuous plate which can be reinforced, as indicated, very simply. Bolted to the flanges of the lower angle pieces 10, is a plate 13 to which are connected the angle members constituting the inner ends of the lateral system 2, thus connecting the lateral systems of both spans to the cross girder in the axis of flexure, or line of no flexure. The spans are further connected with the cross girder by inner and outer corner angles 14, which are riveted to the ends of the span girders and, through the vertical filler members 15, to the cross girder. As clearly shown in Figure 5, the vertical filler members 15 are in two separate sections, and between the adjacent ends of the sections is 05 a horizontal filler member 16, which rests

flush against the flanges of the corner angles and the vertical edges of the span webs. It will be apparent inasmuch as there is no material between the adjacent ends of the span girders above and below the horizontal filler members, the spans may flex slightly under the heavy loads imposed by the rolling stock or due to varying elevations of circular track, this flexing movement taking place of course about an axis passing through the horizontal filler members. This is the axis of flexure, or line of no flexure, referred to above.

The lateral bracing system 2 of both spans (which may be termed the inside system) should be connected with the cross girder in the line of no flexure, and this is effected by connecting the inner ends of said systems with the plate 13 which, as indicated in Figure 5, lies in a plane passing through the horizontal filler members 16, about which the spans flex, as pointed out above. In order to extend the lateral bracing system around the ends of the spans to form a deep truss flange for the two center panels of the table in the plane of no flexure, for sustaining and transmitting the lateral stresses and for the additional purpose of supporting the power intake arch, I provide the outside lateral system indicated diagrammatically in Figure 3, and shown more in detail in the other views. This system in the embodiment of the invention illustrated, comprises angle irons 17, having their inner ends riveted to plates 18 secured to the span webs, and having their outer ends secured to a plate 19, which is connected to the cross girder 4 by means of the horizontal and diagonal members 20 and 21, respectively. The angle members or struts 20, at the inner ends thereof, have their vertical flanges riveted directly to the projecting end of the cross girder and their horizontal flanges riveted to brackets 22 attached to said girder, the horizontal flanges of said angles 20, at the outer ends thereof, being riveted to the plate 19. Secured between the vertical flanges of angles 20, at the outer ends thereof, is a plate 23, to one side of which is bolted the lower end of the diagonal member 21, the upper end of said member being bolted to the cross girder. A plate 24 is riveted to the outer flanges of angle pieces 25, which have their inner flanges riveted to the vertical flanges of members 20 and also to the plate 23 and member 21. The frame just described not only provides, in effect a vertical stay or support for the two central lateral system panels of the table y—y passing through the line of no flexure, but also provides a support for the power-intake arch 26, the bases of said arch being secured to the plates 24. To give additional support to said arch, I provide

the transverse brace consisting of angle pieces 27 and the longitudinally extending brace comprising angle pieces 28. The angle pieces 27 are in pairs, as clearly shown in Figure 7, and have their vertical flanges embracing the projecting end of the cross girder 4, and riveted thereto, the outer ends of said angle pieces being drawn together with their horizontal flanges riveted to a plate 29. Plate 29 is fastened to a vertical plate 30 by means of an angle piece 31, and plate 30 is riveted to the channel plates of the arch. As shown in Figure 7, the plate 30 has an inwardly bent portion at one side, to which is fastened the outer end of the angle brace 28, the inner end thereof being fastened to a plate riveted to the under side of the top flange of the girder B. Because of the slight bending of the table about the line of no flexure, it is obvious that the arch can be braced longitudinally only on one side. I have therefore shown a brace piece 28 extending between one girder only and the arch. This, however, provides a sufficient bracing against longitudinal stresses and at the same time permits the flexing movements of the table, the arch of course moving synchronously with the movements of one span, in this case span B. I do not of course limit my invention to the specific form of arch and bracing therefor illustrated, as it is obvious that various modifications therein may be made as conditions require. For example, if it is desired to have an arch braced more strongly in the plane of the table deck this could be accomplished by constructing the sides of the arch in the form of an A and attaching the inclined leg of the A to suitable brackets riveted to the webs of one of the spans. In the broader aspect of my invention, it is not essential that the outside lateral system and arch support be connected directly with the cross girder as shown since it is obvious that substantially the same result would be effected by connecting said system and support to plates riveted on the sides of the girder webs instead of connecting them to projecting ends of the cross girder.

A consideration of the diagrammatic view, Figure 3, will make clear the essential connections described above. As plainly shown in this view, the lateral system E of the two span girders A and B connects with the cross girder 4 at a point lying in the axis passing through the filler members 16, that is, the axis of flexure, and the lateral system 17-20 coplanar with E, passes around the meeting ends of the spans, or girders, and connects with the webs of the girder elements at the outer ends of the two central panels, thus providing a deep truss flange for these panels

which will sustain and transmit the thrusts of driving and braking the table, while permitting the flexing of the table about the axis 16. It will further be apparent from this view how the flexing of the table prohibits the employment of brace rods 28 on both sides of the arch. While the lateral system, constituted by the inside system E and the outside system 17-20, is shown disposed in a horizontal plane, it is to be understood that said system might be in any plane or combination of planes transverse to the spans providing it passes through the line of no flexure in connecting to and thus passing through the center cross girder. As illustrated in Figure 4, the table is provided with track rails 40 supported by cross ties 41 laid on the upper flanges of the girder elements, and with walkways 42 at the sides of the track. The usual hand rails 43 may be supported slidably in the arch, as indicated in this view, thus dispensing with posts at these points. A collector 44 is disposed at the top of the arch in vertical alignment with the pivotal axis of the table, and the current is collected through this connection and led to the motors at the two ends of the table by insulated conductors passing down and supported by the arch.

I have referred above to an inside lateral system and an outside lateral system, but as a matter of fact there is only one lateral which is widened at the two center panels for the purpose of sustaining and transmitting all resultant lateral forces to the collar which surrounds the fixed base casting. The members 2, Figure 1, while a part of the lateral system, as web members, are more especially lateral thrust or tension members transmitting to the center fixed base casting the traction force of the engine, coming through the deck to the span and through the webs of the span girders to the members 2. It will be understood that the end trucks can take no lateral forces, nor engine traction or braking forces, hence the lateral system must take all such forces and transmit them to the center fixed casting.

While I have described with particularity a structure embodying my invention, I do not intend thereby to limit the invention to the exact details described, but what I claim as new and desire to secure by Letters Patent is:

1. A turntable of the multiple-span type, comprising aligned spans, a cross girder between the ends of said spans, projecting on both sides thereof and flexibly connected therewith about an axis transverse of said spans, said spans each being provided with an inside lateral bracing system connected with said cross girder in a plane including said axis, an outside lateral bracing system connected with each of the projecting ends

of said cross girder in a plane containing said axis and providing, in effect, a continuous horizontal wide truss system extending on both sides and along the central portion 5 of the table.

2. A turntable of the multiple-span type, comprising two spans, a cross girder between the ends of said spans, projecting on both sides thereof and flexibly connected 10 therewith about a transverse axis, said spans each being provided with a lateral bracing system connected with said cross girder in a plane including said axis, and connected with each of the projecting ends of said 15 cross girder in a plane containing said axis and consisting of a system of transverse and longitudinally extending members connected with the projecting end of said cross girder and with the spans at the outer ends 20 of the central panels.

3. A turntable of the multiple-span type, comprising two spans, a cross girder between the ends of said spans, projecting on both sides thereof and flexibly connected 25 therewith about a transverse axis, and a lateral bracing system connected with each of the projecting ends of said cross girder in a plane containing the axis of flexure.

4. A turntable of the multiple-span type, 30 comprising two spans, a cross girder composed of a single reinforced plate between the ends of said spans, projecting on both sides thereof and flexibly connected therewith about a transverse axis lying well above 35 the lower flanges of said spans, a lateral bracing system connected with the projecting ends of said cross girder at the axis of flexure and forming, in effect, a wide lateral truss for the two center panels of the 40 table, and a power-intake arch supported on said lateral system.

5. A turntable of the multiple-span type, comprising two spans, a cross girder composed of a single reinforced plate between 45 the ends of said spans, projecting on both sides thereof and flexibly connected therewith about a transverse axis lying substantially in the vertical plane including the pivot point of the table and well above the 50 lower flanges of said spans, said spans each including a lateral bracing system connected with said cross girder in a plane including the axis of flexure, and having exterior extensions of said lateral system connected 55 with the projecting ends of said cross girder in said last mentioned plane and a power-intake arch supported on said lateral system.

6. A turntable of the multiple-span type, 60 comprising two spans, electric motors disposed at the outer ends of said spans for operating the table, a central cross girder composed of a single reinforced plate between the ends of said spans, projecting on both sides thereof and flexibly connected therewith about a transverse axis lying substan-

tially in the vertical plane including the pivot point of the table, each of said spans including a lateral bracing system connected with said cross girder in a plane including the axis of flexure, and exteriorly connected with each of the projecting ends of said cross girder in said plane, and an aerial system for conveying power to said motors. 70

7. A turntable of the multiple-span type comprising two spans, a cross girder between the ends of said spans, flexibly connected therewith about a transverse axis, a lateral bracing system connected with each of the projecting ends of said cross girder in a line substantially coincident with the axis of flexure, a power-intake arch supported on said lateral bracing system, transverse braces connecting the sides of said arch with said cross girder and longitudinal braces connecting said sides with one of said spans. 80

8. A turntable of the multiple-span type, comprising two spans flexibly connected about an axis adjacent the transverse vertical plane including the pivot axis of the table, a lateral bracing system passing around the adjacent ends of said spans in line with the axis of flexure, and a power-intake arch supported by said lateral bracing system. 90

9. A turntable of the multiple-span type, comprising two spans flexibly connected about an axis adjacent the transverse vertical plane including the pivot axis of the table, a lateral bracing system passing around the meeting ends of said spans in a plane including the axis of flexure, and extending throughout the two center panels of the table, and a power-intake arch supported by said lateral bracing system. 100

10. A turntable of the multiple-span type, comprising two spans flexibly connected about a transverse axis lying adjacent the transverse vertical plane passing through the pivot point of the table, a lateral bracing system passing around the adjacent ends of said spans and including the axis of flexure, a power-intake arch supported by said lateral bracing system and a longitudinal brace connecting said arch with one of said spans. 110

11. A turntable of the multiple-span type, comprising two spans flexibly connected about a transverse axis lying adjacent a vertical plane passing through the pivot point of the table, a lateral bracing system passing around the ends of said spans containing the axis of flexure, and extending throughout the two center panels of the table. 120

12. A turntable of the multiple-span type, comprising in combination, two spans, a central cross girder between the ends of said spans, means securing said spans to said cross girder for flexing movement about a 130

transverse axis, said spans each having a lateral bracing system, connected to said cross girder at substantially the same elevation as the said axis, horizontal struts 5 projecting from opposite ends of the cross girder at substantially the same elevation as the said axis, and brace members extending from the ends of said struts to the spans.

13. A turntable construction including in 10 combination opposite span sections flexibly connected, and outside lateral reinforcements in a substantially horizontal plane comprising struts projecting from opposite sides of the turntable substantially in alignment with the axis of the flexible connection 15 and members extending from the ends of the struts to the sections and connected to the latter at points removed from said axis.

14. A turntable construction including in 20 combination opposite span sections flexibly connected, and outside lateral reinforcements comprising struts projecting from opposite sides of the turntable substantially in alignment with the axis of the flexible connection 25 and members extending from the ends of the struts to the sections and connected to the latter at points removed from said axis.

15. A turntable of the multiple-span type, 30 comprising two spans, a cross girder between the ends of said spans and flexibly connected therewith about a transverse axis, said spans each being provided with a lateral bracing system connected with said cross girder in a plane 35 including said axis, and an exterior portion of said lateral bracing system connected with said cross girder also in a plane including said axis and consisting of a system of transverse and longitudinally extending 40 members connected with the projecting end of said cross girder and with the spans at the outer ends of the central panels.

16. A turntable of the multiple-span type, 45 comprising two spans, a cross girder between the ends of said spans and flexibly connected therewith about a transverse axis, a lateral bracing system connected with said cross girder in a line substantially coincident with the axis of flexure, and a power-intake

arch supported on said lateral bracing system. 50

17. A turntable of the multiple-span type comprising two spans, a cross girder composed of a single reinforced plate between the ends of said spans and flexibly connected therewith about a transverse axis lying well above the lower flanges of said spans, a lateral bracing system connected with said cross girder at the axis of flexure and forming, in effect, a wide truss for the two center panels 55 of the table, and a power-intake arch supported on said lateral bracing system. 60

18. A turntable of the multiple-span type, comprising two spans, a cross girder between the ends of said spans flexibly connected 65 therewith about a transverse axis, a lateral bracing system connected interiorly to said cross girder in a plane including the axis of flexure and extending exteriorly on both sides of said spans, a power-intake arch supported on the exterior extensions of said lateral bracing system, and operating means 70 for said table including an electric motor for driving the outer end of one of said spans.

19. A turntable of the multiple-span type, 75 comprising two spans, a cross girder between the ends of said spans flexibly connected therewith about a transverse axis, a lateral bracing system connected interiorly to said cross girder in a plane including the axis of 80 flexure and extending exteriorly on both sides of said spans, operating means for said table including a motor mounted adjacent the outer end of one of said spans, and an aerial system of current supply for said 85 motor.

20. A turntable of the multiple span type, comprising two spans, a cross girder between the ends of said spans flexibly connected 90 therewith about a transverse axis, a lateral bracing system connected to said cross girder in a plane including the axis of flexure, operating means for said table including an electric motor, and an aerial system of current supply for said motor. 95

In testimony whereof I hereunto affix my signature.

MEIER GEORGE HILPERT.
